UNITED STATES PATENT OFFICE.

ALFRED VISCHER, JR., OF FLORAL PARK, NEW YORK, ASSIGNOR TO WESTERN ELECTRIC COMPANY, INCORPORATED, OF NEW YORK, N. Y., A CORPORATION OF NEW YORK.

CALLING DEVICE.

Application filed December 21, 1920. Serial No. 432,189.

To all whom it may concern:

Be it known that I, ALFRED VISCHER, Jr., a citizen of the United States, residing at Floral Park, in the county of Nassau, State 5 of New York, have invented certain new and useful Improvements in Calling Devices, of which the following is a full, clear, concise, and exact description:

This invention relates to a calling device 10 by which separate groups of impulses may be transmitted.

An object of this invention is to produce a cheap, efficient and compact calling device or impulse sender of the dial type, such as 15 is used for example with automatic telephone systems, and which will transmit calling impulses in uniform cadence and which cannot be speeded up in its operation by the manipulator.

20 This object is accomplished by providing pawls on the finger wheel and the impulse transmitting mechanism which engage on the forward movement of the finger wheel from its normal position. Means are provided so that when the finger wheel is 25 returned to normal independent of the impulse transmitting mechanism, it is locked in that position and cannot be moved forward until the impulse transmitting mechanism returns to normal, then the finger wheel pawl on the forward movement engages with and slides along the other pawl, and is thus rotated and the finger wheel 30 released. A spring is provided which cooperates with the wheel pawl and rotates the same when it is disengaged from the impulse transmitting mechanism pawl in any position other than normal, so that further engagement between the pawls cannot occur 35 40 until the pawl carrying members return to normal where a projection carried by the casing rotates the wheel pawl into an engageable position relative to the other pawl.

This invention will be more clearly understood by reference to the following detailed 45 specifications and accompanying drawings.

Fig. 1 is a cross section of the calling device.

Fig. 2 is a plan view of the device with 50 parts broken away to show the members in their normal positions.

Fig. 3 is a plan of the device after the forward movement.

A casing 1 has any well-known impulse

transmitting mechanism, such for example 55 as shown in Patent No. 1,096,841, May 19, 1914 to W. Kaisling, mounted therein on shaft 19. The impulse transmitting mechanism is operated by spring 20 and the speed of rotation is controlled by a governor, not 60 shown. Carried by the impulse transmitting mechanism is a disk 2 which has a projection 3 on its periphery and a spring 4 attached. Pawl 5 which has a curved face 6 is pivoted to disk 2 at 7 and held in position 65 against a stud 8 by a spring 9. Finger wheel 10 which is rotatably mounted on shaft 19 of the impulse transmitting mechanism has a pawl 11 pivoted thereto at 13. The pawl 11 has a curved face 12. Spring 70 14 is fixed to plate 15 which is attached to the finger wheel 10. The casing member 1 carries a curved projection 16 and a second projection 18 which serves as a stop for the impulse transmitting mechanism and a locking 75 block for the finger wheel 10 when in its normal position.

When the members are in their normal position, the pawl 11 rests against projection 16. Spring 4 bears against stop 18. If the 80 finger wheel 10 is moved forward, pawl 11 slides along projection 16 and the tip engages with pawl 5 and the curved face 12 slides along the curved face 6 thus rotating the pawl 11 so that it passes the locking 85 block 18. When the forward movement is completed and the finger wheel released, the members are carried back to their normal positions by the impulse transmitting mechanism. If the return of the finger wheel is 90 accelerated, pawl 11 is released from pawl 5 and is rotated by spring 14 so that it cannot engage with pawl 5 again until returned to its normal position where it is locked by block 18 and cannot be released until the impulse transmitting mechanism also returns 95 to its normal position. A projection 16 serves to rotate the pawl 11 to a position where on its forward movement it engages with pawl 5.

100 The finger wheel 10 may therefore be returned to normal in advance of the mechanism, in which case it is locked against readvancement until the mechanism has also returned to normal whereupon the finger 105 wheel is released as described above. If without the mechanism being returned to normal the finger wheel 10 is advanced after

it has been accelerated, there will be no engagement between pawls 5 and 11 and therefore no effect on the movement of the transmitting mechanism and it will be necessary to return finger wheel 10 to normal before further impulses can be sent.

What is claimed is:

1. In a calling device, an electrical impulse transmitting mechanism, a rotatable finger wheel for operating said impulse transmitting mechanism, means to connect said wheel to said impulse transmitting mechanism when the wheel is moved forward from its normal position, and means to disengage said wheel from said impulse mechanism upon the acceleration of said wheel during its return movement, said means preventing readvancement of said mechanism upon the forward movement of said wheel from any position other than normal.
2. A calling device comprising a casing, an impulse transmitting mechanism mounted in said casing, a rotatable finger wheel for operating said transmitting mechanism, a pawl carried by said finger wheel, a second pawl carried by said impulse transmitting mechanism and adapted for sliding engagement with the finger wheel pawl when said wheel is moved forward from its normal position, and a spring cooperating with said

wheel pawl to rotate the same when disengaged from said impulse transmitting device pawl so as to prevent engagement between the pawls when said finger wheel is moved forward from any position other than normal.

3. A calling device comprising a casing, an impulse transmitting mechanism mounted in said casing, a rotatable finger wheel for operating said transmitting mechanism, a pawl carried by said finger wheel, a second pawl carried by said impulse transmitting mechanism and adapted for sliding engagement with the finger wheel pawl when said wheel is moved forward from its normal position, a curved member carried by said casing for holding said wheel pawl in a position so it will engage with said impulse transmitting mechanism pawl when said wheel is moved forward from its normal position, and a spring carried by said wheel and cooperating with said wheel pawl to rotate the same when disengaged from said impulse transmitting mechanism pawl so as to prevent engagement between the pawls when said finger wheel is moved forward from any position other than normal.

In witness whereof, I hereunto subscribe my name this 17 day of December, A. D. 1920.

ALFRED VISCHER, JR.
